Primary Examiner — Antoine Duval Davis(74) *Attorney, Agent, or Firm* — Carter, Deluca & Farrell LLP(57) **CLAIM**

The ornamental design for a thermometer, as shown and described.

DESCRIPTION

FIG. 1 is a front perspective view of a thermometer with a probe in a stored configuration in accordance with the present design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom perspective view thereof; and,

FIG. 9 is a front perspective view of the thermometer with a probe in an unstored configuration in accordance with the present design.

The broken lines shown in the drawings illustrate portions of the thermometer that form no part of the claimed design.
